UNITED STATES PATENT OFFICE.

CLIFFORD A. MCKUNE, OF SAN FRANCISCO, CALIFORNIA.

CLOTHESPIN.

Application filed November 7, 1923. Serial No. 673,323.

To all whom it may concern:

Be it known that I, CLIFFORD A. MCKUNE, a citizen of the United States, residing at San Francisco, in the county of San Francisco and State of California, have invented new and useful Improvements in Clothespins, of which the following is a specification.

This invention relates to improvements in clothes pins and has particular reference to a device for hanging clothes upon a line.

The principal object of this invention is to produce a device of this character which will efficiently hold the clothes against accidental removal.

Another object is to produce a device which will not mutilate the clothes and further to provide means so that the clothes will not come into contact with the clothes line, which is usually soiled.

A still further object is to produce a device of this character which is simple in construction and therefore cheap to manufacture.

Other objects and advantages will be apparent during the course of the following description.

In the accompanying drawings forming a part of this specification, and in which like numerals are employed to designate like parts throughout the same,

Figure 1 is a front elevation of my clothes pin.

Figures 2, 3 and 4 are side views showing the manner of connecting the clothes with the pin.

In the placing of clothes upon a line, it often happens that the clothes become soiled, due to the contact with the line which is dirty, and furthermore, the average pin is liable to slip and therefore the clothes are blown away or lost. This is particularly true during a heavy wind.

I have therefore sought to devise means whereby the clothes may be held upon the line without becoming soiled and at the same time without there being any danger of their being disengaged through the action of the wind. It is possible with my device to place the pins upon the clothes previous to carrying the same out of doors, which is a great advantage, particularly, when the weather is cold and, consequently, the hands become numb from handling the wet clothes.

In the accompanying drawings wherein for the purpose of illustration is shown a

preferred embodiment of my invention, the numeral 5 designates a substantially rectangular loop having a straight portion 6. This loop is preferably formed of wire 60 twisted together, as shown at 7, and having its ends bent rearwardly, as shown at 8 and 9, thence downwardly as shown at 11 and 12, terminating in curved ends 13 and 14. Thus the ends of the wire form hooks for suspending the device upon a line.

A yoke-shaped member 16 is hingedly connected with the member 5 by having its ends bent to form eyes for receiving the upper portions of the member 5. The member 16 70 is provided with extended ends 17 and 18 which engage the end pieces of the member 5 and prevent the said member 16 from passing through the member 5. Another yoke-shaped member 19 is hingedly connected 75 with the part 6 of the member 5 by having eyes formed at its ends for receiving said part 6. As shown, the member 16 engages the opposite side of the member 5 from that on which the hooks are arranged.

In attaching the pin to the clothes a part of the article, which is shown at A, is passed through the member 5 and downwardly through the member 19, said member 19 being swung upwardly, as shown in Figure 2 85 to facilitate the placing of the article in the device. The member 19 is then swung downwardly and upwardly, as shown in Figure 3, until it passes through the member 5 and by the member 16. The member 16 will 90 swing upwardly, as shown in dotted lines in Figures 2, 3 and 4, as the member 19 is passed through the member 5 and then said member 16 will drop back against the member 5 and prevent the return of the member 95 19. Thus the article of clothing has a portion clamped between the members 19 and 16, as shown in Figure 4, and the greater the pull on the article the greater the clamping effect will be. The looped part of the article is wrapped around the member 19 and the double portion of the article is clamped between the members 16 and 19. Thus the article of clothing is firmly held by the device and there is no danger of it becoming 100 separated therefrom.

As before stated, the devices can be attached to the clothes before the clothes are carried to the line so that it is simply necessary to place the hooks over the line when 110 the clothes are carried outside to the line.

If desired, the member 19 can be given

several turns to wrap more of the article around the same though this will not be necessary in most cases.

It will thus be seen that I have produced a device which is simple in construction and one which may be easily applied to the clothes to be hung upon the line. It will also be noted, that the clothes line is a considerable distance away from the clothes being held, therefore preventing the soiling of the clothes. It will also be seen that the device with the clothes attached thereto may be readily hung upon the line as is customary with any hooked device.

15 It is to be understood that the form of my invention herewith shown and described is to be taken as a preferred example of the same, and that various changes in the shape, size and arrangement of parts may be resorted to without departing from the spirit 20 of the invention or the scope of the subjoined claims.

What I claim is:—

1. A device of the class described comprising a frame part, a stop member hingedly connected therewith and having a part for engaging one side of the same and a clothes engaging member rotatably connected with the bottom portion of the frame and adapted to be passed through the same and by the stop member so that the stop member will prevent the return movement of the said member.

2. A device of the class described comprising a frame part, a stop member hingedly connected therewith and having a part for

engaging one side of the same, a clothes engaging member rotatably connected with the bottom portion of the frame and adapted to be passed through the same and by the stop member so that the stop member will prevent the return movement of said member and suspending means at the top of the frame.

3. A device of the class described comprising a frame having hooks formed at its upper end, a stop member hingedly supported by the frame and having a portion engaging one side of the frame, a clothes engaging yoke-shaped member having its ends 45 rotatably connected with the bottom piece of the frame and adapted to be swung through the frame and past the stop member so that said stop member will prevent the return movement of the same.

4. A device of the class described comprising a substantially rectangular frame formed of wire and having suspending hooks formed at its upper end, a yoke-shaped member having eyes at its ends 60 which engage the upper part of the frame, said member having its ends extended to engage the ends of the frame, a second yoke-shaped member having eyes at its ends which engage the bottom piece of the frame 65 for receiving the clothes and which is adapted to be passed through the frame and past the first member so that the clothes will be clamped between the two members.

In testimony whereof I affix my signature.

CLIFFORD A. MCKUNE.
